UNITED STATES PATENT OFFICE.

FRANK T. RILEY, OF KANSAS CITY, MISSOURI.

TALLY.

1,090,346.

Specification of Letters Patent. Patented Mar. 17, 1914.

Application filed April 9, 1912. Serial No. 689,636.

To all whom it may concern:

Be it known that I, FRANK T. RILEY, a citizen of the United States, residing at Kansas City, in the county of Jackson and State of Missouri, have invented certain new and useful Improvements in Tallies; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to a method of tabulating games, and more particularly information relating to and the results of base ball games, the principal object of the invention being to provide a method of tabulating whereby information relating to a number of games may be printed in a limited space.

20 It is well known that a great many people are interested in the results of base ball games in one and often in several of the many base ball leagues, and take pleasure in referring to the score sheets of games 25 played in previous years. In order to satisfy this demand, and also to provide permanent records of the games in major and 30 many minor leagues, books have been published containing information in some detail regarding the major leagues and in a more general way regarding the smaller league clubs. In order, however, to include sufficient 35 information to give such records any value for general circulation, it has been necessary to provide a book of such bulk that it is inconvenient to carry and expensive to produce. To obviate these disadvantages, I 40 have devised a method of tabulating information relating to the games whereby the material points may be given in a very limited space, thereby enabling the publisher to include information regarding more games 45 in less space and at less expense than has heretofore been possible.

The material points of the game, which should be made a matter of record are, of course, the number of runs, hits and errors 50 made by respective contesting teams, the pitchers used and the dates when the games were played. To arrange this information compactly, and in a manner to be readily understood, I treat each league separately, 55 under proper headings, in the manner shown in the accompanying drawings, which show

the beginning of a table for the present American Base Ball League. At the head of the table is a list of the pitchers of the league, each name being preceded by a number which is used in the following table to designate that particular pitcher, the pitchers for each club being grouped in the sequence of their club records, and the clubs being arranged in the order in which they 60 finished the season for which the record is made. 65

In the table following the pitchers' list, one of the clubs is selected and paired in vertical alinement with each of the other clubs of the league, the basic club being preferably, but not necessarily, the one finishing first in the league race, and the others following in the order of their standing.

More specifically referring to the drawings, the first pair shows Washington—the basis of this group—in heavy type at the top and "At Detroit" immediately therebelow in smaller type, indicating that the following information relates to games played between 75 Washington and Detroit on the latter's 80 ground.

Following the names of the teams, in horizontal alinement, appear the figures

4	85			
5/22	7	18	1	
			5	
3	6	3		

the coupled figures 5/22 indicating that a 90 game was played on the twenty-second day of the fifth month, or May 22, of the year for which the book was published. The figures 7 3 18 95 designate the number of runs, 6 the number of hits and 3 the number of errors made by the respective teams, and the index figures 4 5 following the error figures designate 100 the pitchers used in the game. By referring to the pitchers' list we see that the Washington pitcher, whose number is 4, was Walker and the Detroit pitcher numbered 5 was Lafitte. In this way we are quickly informed that on May 22, Washington played Detroit at Detroit, that Washington won by the score of 7 to 3, making 18 hits and 1 error to 6 hits and 3 errors by Detroit, and that Walker worked for Washington against 105 Lafitte for Detroit. Following this information is a single vertical column followed

110

by other score figures and different pitcher indexes, but without a new date couplet, indicating that the teams were playing a series at Detroit. By the method described, we 5 are informed that this second game was won by Detroit, the score being 9 to 8, and that Detroit made 12 hits and 3 errors to 13 hits and 3 errors by Washington. We are also informed by the single index in the Detroit 10 column that No. 3, or Mullin, pitched for Detroit. In the Washington line, however, we find two indices, arranged in upper and lower positions. This means that No. 5 pitcher, or Gray, started the game for Washington but was relieved by No. 1, or Johnson, who finished; the upper index figure designating the pitcher who received credit for the game.

Two other games are recorded in like manner, the fourth game record being followed 20 by a double vertical line to indicate the closing of the series. The game record following the double lines is preceded by a date 7/7, showing the commencement of another 25 series of games between Washington and Detroit on the latter's ground. Later in the column for these clubs we find two games recorded in heavy type. This indicates a double header or that two games were played 30 on the same day.

Following the horizontal column described, Washington is paired with each of the other teams in the league and a record 35 of the series and games is made, as described with reference to the games played between Washington and Detroit.

After the Washington pairings, another team is selected and paired in like manner and so on until the table is completed.

40 Having thus described my invention, what I claim as new therein and desire to secure by Letters-Patent is:

1. A tally sheet having a division giving the names of different teams and the names 45 of players, the names of players on each team being numbered and grouped after the name of the team, a column wherein the names of teams are paired, and paired columns of figures following the names of the 50 paired teams, sets of the figure columns being separated and each set in the figure column having an index number corresponding to the number of a player in the name division.

55 2. A tally sheet having a division giving the names of different teams and the names of players, the names of players on each team being numbered and grouped after the name of the team, a column wherein the 60 names of teams are paired, and paired col-

umns of figures following the names of the paired teams, sets of the figure columns being separated and each set in the figure column having an index number corresponding to the number of a player in the name 65 division, and some of the index numbers being in turn indexed, for the purpose set forth.

3. A tally sheet having paired columns headed by the names of contesting teams, 70 sets of figures following the team names in paired relation, some of the sets of figures being differentiated from the other sets, and each set of figures being indexed for the purpose set forth.

4. A tally sheet having paired columns headed by the names of contesting teams, sets of figures following the team names in paired relation, some of the sets of figures being printed in type heavier than that used 80 for other sets, and each set of figures being indexed for the purpose set forth.

5. A tally sheet having paired columns headed by the names of contesting teams, sets of figures following the team names in 85 paired relation, minor division markings between said sets, major division marks between different series of sets, each set of figures being indexed and a date marking for each series.

90 6. A game table comprising the names of contesting teams arranged in pairs, and sets of figures arranged in paired relation following the names, the separate sets of figures being set off from each other the type 95 for some of the sets being heavier than that for other sets, and each set of figures being indexed for the purpose set forth.

7. A tally sheet comprising a division wherein the names of teams and players are 100 arranged with the names of the players numbered and grouped after the name of the team, a division wherein the name of each team is paired with that of each of the others, paired columns of figures arranged 105 in sets and following the paired names of the teams, numbers following each set of figures and corresponding with the numbers indicating the names of players in the first division, minor division marks separating 110 each set of figures, major division marks separating the sets into series, and date figures preceding each series, substantially as set forth.

In testimony wheroft I affix my signature in presence of two witnesses.

FRANK T. RILEY.
